Iver Anderson
BY
Augustus P. Stone of Boston
ATTORNEY.

UNITED STATES PATENT OFFICE.

IVER ANDERSON, OF QUAKERTOWN, PENNSYLVANIA, ASSIGNOR TO PEABODY LEATHER COMPANY, INC., OF QUAKERTOWN, PENNSYLVANIA, A CORPORATION OF NEW JERSEY.

WAIST BELT.

Application filed January 17, 1927. Serial No. 161,559.

The principal object of the present invention is to improve the appearance, more particularly the appearance of the edges, of waist belts made of a solid piece or strip of bridle or strap leather, and according to the invention that object is attained by marginally grooving the flesh side of the leather of the belt to provide a feather edge and space for its reception and folding the feather edge into the space to present the hair or grain side not only at the edges but also at the front face.

The invention also comprises the improvements to be presently described and finally claimed.

In the following description reference will be made to the accompanying drawing forming part hereof and in which

Figure 1 is a view of one face, the face that usually confronts the body of the wearer, of a part of a waist belt embodying features of the invention.

Fig. 2 is a similar view showing the feather edges and the space for their reception.

Fig. 3 is a transverse sectional view of Fig. 2 drawn to an enlarged scale.

Fig. 4 is a transverse sectional view of Fig. 1 drawn to an enlarged scale.

Fig. 5 is a view similar to Fig. 1 but showing stitching.

Fig. 6 is a transverse sectional view similar to Fig. 4 but showing a lining, and

Fig. 7 is a top view of Fig. 6 but showing stitches.

In the drawing there is shown a solid strap leather waist belt in which the grain side appears at the edges as well as on one face. 1 indicates a solid piece or strip of

strap or bridle leather and it is marginally grooved on the flesh side to provide a feather edge 2 and a space 3 for the reception of the feather edge. The feather edge 2 is folded into and secured in the space 3 to present

the grain side at the edges. The feather edge may be secured in any appropriate way as by pasting or cementing, Figs. 4 and 6, or as by stitching 4, Figs. 5 and 7. If desired use may be made of a lining 5, Fig. 6, and

it can be secured in a similar manner. Of course the width of the belt and the width of the feather edges are matters of taste and

the leather employed is also a matter of fancy and it may be smooth grain leather, or embossed leather, or colored leather, or natural leather, or, in fact, any kind of leather.

It will be obvious to those skilled in the art to which the invention relates that modifications may be made in details of construction and arrangement and in matters of mere form without departing from the spirit of the invention which is not limited to such matters or otherwise than the prior art and the appended claims may require.

I claim:

1. A waist belt comprising a solid strip of strap leather marginally grooved on the flesh side and providing a feather edge and space below the level of the flesh side for its reception and having the feather edge folded into and secured in said space to present the grain side at the edge.

2. A waist belt comprising a solid strip of strap leather marginally grooved on the flesh side and providing a feather edge and space below the level of the flesh side for its reception and having the feather edge folded into and secured in said space to present the grain side at the edge, and a line of stitching passing through the folded feather edge and the strap leather.

3. A waist belt comprising a solid strip of strap leather marginally grooved on the flesh side and providing a feather edge and space for its reception and having the feather edge folded into and secured in said space to present the grain side at the edge, and a lining overlying the folded feather edge and the flesh side of the strap and secured thereto.

4. A waist belt comprising a solid strip of strap leather marginally grooved on the flesh side and providing a feather edge and space for its reception and having the feather edge folded into and secured in said space to present the grain side at the edge, a lining overlying the folded feather edge and the flesh side of the strap and secured thereto, and a row of stitches passing through the lining and the feather edge and the strap leather.

IVER ANDERSON.
